UNITED STATES PATENT OFFICE.

FRANCIS E. VAUGHN AND MARION E. VAUGHN, OF PENDLETON, INDIANA.

GAS-ENGINE.

SPECIFICATION forming part of Letters Patent No. 716,792, dated December 23, 1902.

Application filed June 29, 1901. Serial No. 66,467. (No model.)

To all whom it may concern:

Be it known that we, FRANCIS E. VAUGHN and MARION E. VAUGHN, of Pendleton, county of Madison, and State of Indiana, have invented a certain new and useful Gas-Engine; and we do hereby declare that the following is a full, clear, and exact description thereof, reference being had to the accompanying drawings, in which like numerals refer to like parts.

The object of our present invention is to improve the construction and operation of gas or gasolene engines.

Our invention consists in a reversible gas or gasolene engine, and to accomplish that object one new feature lies in the automatic operation of the fuel-inlet valve by the crank on the crank-shaft or any part connected with or controlled by the piston, whereby the engine can be reversed.

Another feature of the invention coöperating with the foregoing to produce the result mentioned consists in a double cam for controlling the sparker-actuating mechanism, so that it will be equally operative when the engine is reversed or in whichever direction the engine may be operated.

These features of our invention will appear more fully from the accompanying drawings and the following description and claims.

Figure 1 is a plan of the engine. Fig. 2 is vertical section on the line 2 2 of Fig. 1, being a side elevation of the major part of the engine. Fig. 3 is a central vertical longitudinal section of the engine. Fig. 4 is a vertical cross-section through the engine on line with the crank-shaft. Fig. 5 is a vertical cross-section of the crank-shaft, showing in side elevation the fly-wheel on which the governor is mounted, parts being broken away. Fig. 6 is a vertical cross-section on the line 6 6 of Figs. 1 and 7, showing the gasolene-mixer. Fig. 7 is a horizontal section on the line 7 7 of Fig. 6, showing it arranged for gas. Fig. 8 shows the cam for controlling the sparker-actuating device, said cam being shown in said figure in elevation and also in plan. Fig. 9 shows the inlet-valve for the fuel after the piston has made its forward movement. Fig. 10 shows the fuel-inlet-valve mechanism altered when the engine is reversed from the position of the parts in Fig. 3.

Fig. 11 is a longitudinal section of the means for mounting the sparker. Fig. 12 is an enlarged section of the top front part of the piston at the limit of its inward stroke and the adjacent part of the cylinder. Fig. 13 is a plan of the cam for actuating the sparker mechanism and the adjacent parts, parts being broken away to show the position of the sparker-actuating rod on the cam after an ignition.

Referring now to the details of construction of the horizontal engine which we have shown in the drawings for the purpose of illustrating the general nature and principles of the various improvements we have made and hereinafter claim, the bed-plate 1 is mounted upon a suitable base, and upon that bed-plate and integral with it is the casing 2, which encloses the piston-rod 3 and piston 4 and is integrally connected with the cylinder 5. In fact, the chamber formed by the casing 2 and the cylinder 5 are all one chamber when the piston is out. 6 is the cylinder-head, which is removably secured to the cylinder. A water-jacket 7 surrounds the combustion end of the cylinder. The water flows into it through the pipe 8 below and out through the pipe 9 above.

10 is the inlet-port for the fuel to the combustion end of the cylinder, and the fuel is conveyed to said port through the passage 11 from the chamber formed by the casing 2. The inlet 10 is on the upper side of the cylinder when the engine is horizontal, and the exhaust-port 12 is on the lower side, the pipe 13 leading from said exhaust-port.

The piston is hollow to receive the piston-rod, which is pivoted on the pin 14, extending through the piston transversely, and the bearing-block 15 is held against the end of the piston by a set-screw 16, that extends through the head of the piston. The head of the piston is reinforced by the plate 17, which has on its upper side the forwardly-projecting lip 18, extending about one-fourth the way around in the arc of a circle, with its upper surface concave in a section longitudinal of the piston, whereby the fuel entering through the inlet-port 10 when the piston is at its rear limit of movement will be deflected upward, as seen in Fig. 12, and away from the exhaust-port at the under side or bottom

of the cylinder, and thus its escape through said exhaust-port is prevented. Said piston is provided with suitable packing and otherwise constructed in ways familiar to those skilled in the art, which constitute no features of novelty.

The crank-shaft 20 extends transversely through the casing 2 and about concentric therewith, being mounted in the bearings 21 10 and 21, bolted to each side of said casing, as appears in Fig. 4. A pair of fly-wheels 22 and 23 are secured on said shaft, one with the handle 24 for starting the engine and the other 22 carrying the governor device.

15 In the bearing 21 to the left of the engine, as shown in Fig. 4, the fuel-inlet mechanism is provided. The casing 2 on that side is cut away annularly to receive the annular flange 25 on the inner end of the bearing 21, as appears in Fig. 7. Through the inner wall of this bearing 21 three passage-ways or openings are provided, as seen in Fig. 7, a central one 26 for the passage of gas or gasoline, and the opening 27 on each side thereof from the 20 outside to introduce air into the chamber in the casing 2 to commingle with the gas, and thereby make it combustible. The air-openings 27 are closed when gasoline is used, as the air is previously mixed with the gasoline 25 by what is shown in Fig. 6, and the resultant gas passes through the opening 26. As seen in Fig. 7, the opening 26 leads from the chamber 28, that is supplied with gas through a suitable supply-pipe (not shown) or gasoline 30 through the pipe 38. (Seen in Fig. 6.)

The mixing-chamber 30 is formed by the valve-casing 31, vertically bored out, with the large chamber opening at the upper end and the smaller opening or air-inlet 32 through 40 the lower end. The upper opening is closed by the screw-plug 33 and has in it a guide-hole 34 for the stem of the valve 35. The hole 34 is closed at the upper end by the screw 36. The valve 35 by gravity closes 45 the air-inlet opening 32 and also the gasoline-inlet port 37, that leads from the gasoline-supply pipe 38, and is controlled by the needle-valve 39. The valve 35 is raised by suction of the engine to admit the gasoline 50 and air.

The inlet-ports 26 and 27 for the gas and air are closed by a revoluble valve-plate 40, that surrounds the shaft 20, and also a small collar 41, extending inward from the bearing 21, as seen in Fig. 4, and lies between said collar 41 and the annular collar 25 from said bearing, as shown in Figs. 4 and 7. Said valve-plate is a plain disk and has in it a slot 42 in the arc of a circle and concentric with the 55 valve-plate, as appears in Figs. 3, 9, and 10. This valve-plate 40 is rotated by the crank of the crank-shaft engaging one of the pins 43 that extend inward from said plate, as appears in Figs. 3 and 4. At each rotation of 60 the valve-plate the slot 42 passes and registers with the inlet-ports 26 and 27 for the gas and air, and during such time the chamber in

the casing 2 is charged with fuel. This is while the piston is moving forward. After the explosion and return movement of the 70 piston the gas and air in the chamber within the casing 2 is somewhat compressed, and when the piston has retreated enough to uncover the inlet-port 10 such gas and air rushes through the passage-way 11 and through said 75 port into the forward end of the cylinder. Just before this is done the forward end of the cylinder is exhausted of the gases resulting from the explosion through the exhaust-port 12. The forward movement of the piston 80 immediately following closes both the inlet and exhaust ports and compresses the gas and air in the forward end of the cylinder ready for and prior to its ignition by the electric spark. By providing two pins 43 in the 85 valve-plate 40 so placed that the crank-shaft can be reversed without the actuation of said plate 40 during the reversal or semirotation of the fly-wheel and crank-shaft. At the end 90 of such reversal or semirotation the crank-shaft engages one of the pins 43 and actuates the plate 40 continuously until another reversal of the engine. Said pins 43 are so placed that the valve-plate by means of the slot 42 will uncover the inlet-ports 26 and 27 95 for the fuel while the piston is moving forward. By the valve-plate 40 not being actuated during the reversal of the engine such reversal is made possible, because the fuel then does not enter at the wrong end of the 100 stroke of the piston, but when the semirotation of the shaft or the reversal of the engine has been consummated the inlet of fuel will occur at the proper time—that is, on the forward stroke of the piston—just the same as 105 prior to the reversal of the engine.

The igniting device is shown on the cylinder-head in Fig. 3. Extending centrally through said cylinder-head there is a sleeve 50, through which a contact pin or point 51 110 extends and which is insulated from the sleeve 50, as appears in Fig. 11. To this point 51 an electrical conductor or wire 52 is secured. Within the cylinder a post 49 is mounted on the inner end of the sleeve 50, and in that 115 post a horizontal shaft 53 is mounted, carrying an arm or contact-point 54, which normally is in contact with the inner end of the contact-point 51. When the contact between the contact-point 51 and 54 is broken by the 120 means hereinafter described, the spark is emitted that explodes the gas in the cylinder.

The shaft 53, just referred to and shown in Fig. 3, extends outside the cylinder, as shown in Fig. 2, and on its outer end carries a crank 125 55, which is operated by the rod 56, that extends loosely through it and is held in place by the nut 57 on one side and the spiral spring 58 on the other side, said spiral spring 58 acting against the washer 73 at one end and 130 against the stationary collar or block 59 at the other end. The rod 56 is guided through an apertured bracket 60, secured to the side of the engine-casing, and is actuated by the

cam 61. The opening in the guide-bracket 60 is large enough to permit a slight lateral movement of the rod 56 toward or away from the engine-casing, as appears in Figs. 1 and 5 13, and through the opening in said bracket 60 a flat spring 62 extends, it being curved, with one end secured to the rod 56 and the other end resting against said rod, with the swell bearing against the inner end of the 15 slot or opening in the bracket 60. The object of the spring 62 is to hold the rod 56 at its outer limit of movement and on the outer periphery or collar of the cam 61, as appears in Fig. 1. Said cam 61 is secured on the shaft 15 20 and rotates therewith. It is shown in detail in Fig. 8. It has two peripheries, an outer periphery concentric with the center of the shaft on which the cam is mounted and which at one point is cut away to permit the 20 25 end of the rod 56, by reason of the action of the spring 58, to escape from such outer periphery or collar and extend through such cut-away portion against the inner or secondary periphery 65. The latter is eccentric 25 30 with the shaft 20 and with the outer periphery of the cam 61, as appears in Fig. 8. The surface of said eccentric collar or periphery that is nearest the center of the shaft 20 is located adjacent the notch or cut-out 30 35 portion of said outer periphery, as appears in Fig. 8. The portion of the inner or eccentric periphery of the cam 61 that is farthest from the center of the shaft is flush with said outer periphery, as appears in Fig. 8. As has been 35 40 explained, the end of the rod 56 is pressed and rides against the outer periphery of the cam 61 until it drops into the cut-out portion thereof, and then the contact-point 54 (shown in Fig. 3) is separated from the contact-point 40 45 51, and the spark occurs. The cut-away portion or recess in the outer periphery of the cam 61 has at both ends of it an inclined surface 65, and as said cam rotates farther each inclined side surface pushes the inner end of 45 50 the rod 56 toward the casing of the engine, as appears in Fig. 13. During such operation the inner end of the rod 56 abuts against the inner or eccentric periphery of the cam. The further rotation of said cam causes the inner 50 55 end of said rod 56 to ride around to the portion of the inner or eccentric periphery that is flush with the outer periphery of said cam, and when it does so the spring 62 pushes the inner end of said rod 56 out and causes it 55 60 subsequently to ride upon or against the outer periphery, until it again falls into the notch or recess in the outer periphery, and another spark is emitted. The object of this construction of the cam having the outer periphery 60 65 notched or recessed with the two oppositely-inclined side faces 65 is to enable the sparking mechanism to operate in the same way when the engine is reversed or regardless of the direction in which the engine is running. 65 The governor in this engine is mounted upon the fly-wheel 22, as illustrated in Figs. 4 and 5, and it acts as a governor by interrupting the flow of the electric current to the sparking contact-point 54. As will be observed in said figures, we mount upon the shaft an insulated collar 80 having a groove in its periphery in which lies an electrical conductor 81, a wire or spring that is held in place by the staples 82 upon the base-piece 85 and insulated therefrom. Conductor 81 is connected 70 75 with a suitable battery or dynamo for generating electricity, which, however, is not shown. In the machine here shown the electric circuit between the wire 83, just mentioned, and the wire 52 at the cylinder-head 80 is established by means of and through the engine—that is, the fly-wheel, shaft, and engine-casing. The circuit between the fly-wheel and collar 80, that is connected with the conductor 81, is completed by the rod 86, 85 which is mounted in the fly-wheel, as shown in Fig. 5. It is pressed inward by the spring 87 through the guide 88 against the periphery of the collar 80. As long as there is contact between the rod 86 and the collar 80 the 90 circuit is closed for sparking purposes. When the speed of the engine becomes great, the centrifugal force of the fly-wheel 23 will throw the rod 86 outward against the spring 66 and disengage it from the collar 80. This 95 breaks the circuit and stops the sparking and the explosion of gas in the cylinder, and consequently reduces the speed of the engine until the spring 87 overcomes the centrifugal force acting on the rod 86 and pushes said 100 rod back into contact with the collar 80 and closes the circuit, whereupon the sparking and the explosion of the gas will be resumed. While the sparking-circuit is broken by this 105 governor during the high speed of the engine, the introduction of the fuel into the forward end of the cylinder is no greater than usual, because the exhaust-port permits the escape of any surplausage.

The desired speed of the engine can be regulated through means of the screw 89. When it is desired to decrease the speed of the engine, said screw is loosened somewhat to diminish the tension of the spring 87, whereby the centrifugal force of the wheel acting on 110 the rod 86 will more readily overcome the action of the spring and said rod be moved out of contact with the collar 80 to break the circuit. On the other hand, if the screw 89 be tightened a correspondingly higher speed of 115 the engine would be required to break the circuit. In order to distribute and mix the incoming gas and air, we place diagonally-extending bars 72 across the slot or inlet 42 of the valve 40, as shown in Figs. 9 and 10. 120

What we claim as our invention, and desire to secure by Letters Patent, is—

1. A gas-engine including a fuel-inlet, a rotary valve for opening and closing said inlet, a rotary piston-actuated means, and a pair of 130 stops on said valve, one of which is engaged by the piston-actuated means while revolving

in one direction, and the other is engaged by said means while revolving in the other direction.

2. A gas-engine including a fuel-inlet, a rotary valve for opening and closing said inlet, a rotary piston-actuated means for actuating the valve, and a connection between the piston-actuated means and valve so located that the piston-inlet will be open while the piston 10 is moving forward and while reversing said valve will not be operated.

3. A gas-engine including a crank-shaft, a fuel-chamber connected with the cylinder of the engine and through which said crank-shaft extends, a fuel-inlet opening in the wall of said chamber, a valve-plate rotatably mounted concentric with the crank-shaft adapted to open and close said fuel-inlet, and a pair of stops on said valve-plate that are 15 singly engaged by the crank on the crank-shaft, said stops being so placed with relation to each other that the crank on reversal will make a half-revolution from one of said stops before it engages the other stop, substantially 20 as shown.

4. A gas-engine including a crank-shaft, a fuel-chamber connected with the cylinder and through which said crank-shaft extends, a curved fuel-inlet opening through the wall of said chamber concentric with the crank-shaft, 30 a valve-plate rotatably mounted concentric with the crank-shaft and having a curved opening therein to register with the opening through the wall of the fuel-chamber, the pins 43 connected with said valve-plate substantially as shown on the same side of a diametrical line through the center of said valve-plate, and in position to be engaged by the crank on the crank-shaft, and a piston-rod connected with the crank on said crank-shaft 35 for actuating the same.

In witness whereof we have hereunto affixed our signatures in the presence of the witnesses herein named.

FRANCIS E. VAUGHN.
MARION E. VAUGHN.
